UNITED STATES PATENT OFFICE

2,431,502

MOP HEAD ADAPTED TO BE DETACHABLY CONNECTED TO A MOP HOLDER

Walter Podolak, Chicago, Ill., assignor to Boyle-Midway Inc., Chicago, Ill., a corporation of Delaware

Application March 8, 1945, Serial No. 581,607

1 Claim. (Cl. 15—228)

1

This invention relates to a novel means for the expeditious separable connection of a mop head and handle.

It is generally aimed to simplify such a connection without sacrifice of durability and efficiency, to the end that the article may be manufactured inexpensively and expeditiously in large quantities with modern machinery.

More specifically, an object is to provide a novel means including a frame disposed in approximately a single plane which may be attached and detached by a threading action into and out of the retaining space provided between relatively close parallel webs, and which space is bordered by a ring or barrier which co-acts with a split ring or one element of the frame during the threading operation mentioned, and which permits relative rotation of the mop head and handle at all times so as to avoid undue strain of one such part on the other in use.

A further object is to provide the frame of such construction that it will sufficiently reinforce the attached mop that the latter may be made entirely of textile fabric or equivalent flexible material usually stitched together so that the cost of manufacture may be maintained at a minimum and the mop head may be easily washed. Additionally, an object is to provide the frame in the form of a split or discontinuous approximately annular wire having the terminals thereof slightly spaced apart and having a diametral portion continued from one of said terminals, and on which a handle socket is mounted, preferably pivotally.

Various additional objects and advantages will become apparent from a consideration of the description following, taken in connection with the accompanying drawings illustrating an operative embodiment by way of example. In said drawings:

Fig. 1 is a perspective view of a connected mop head and handle attaching means according to the invention;

Fig. 2 is a view taken through the parts of Fig. 1 on substantially a diametral section, a portion of a handle proper being included;

Fig. 3 is a plan view showing the handle connection in connection with the mop head in the act of application of the former to the latter; and

Fig. 4 is a diametral sectional view through the same parts as Fig. 2 taken approximately at a right-angle thereto.

Referring specifically to the drawings wherein like reference characters designate like or simi-

2

lar parts, a mop head is shown at 10, which generally may be of any suitable construction. The strands or mop elements are shown at 11, being of textile or equivalent material and the head 5 also includes a pair of round disks or webs 12 and 13, also preferably of textile fabric or equivalent material, and which are connected together marginally only, as by the use of textile thread or the equivalent at 14.

Except for the line of stitching 14, which forms a ring or annular barrier, the webs 12 and 13 are unconnected and therefore provide a space between them as at 15 to accommodate a suitable handle connection which is adapted to be inserted and removed by the aid of an opening 16 provided in the web 13.

The handle connection is generally designated 17. It may consist of a frame provided by a metallic wire or other ring 18, whose external diameter is the same as the internal diameter of the ring or barrier 14. Ring 18 is in one piece or split and at one terminal has a diametral arm 19. The distal end of the ring 18 is preferably slightly spaced from the arm 19 and returned or otherwise rounded as at 20 while the distal end of the arm 19 is preferably returned or otherwise rounded as at 21. A socket or equivalent attaching means for a wooden or equivalent staff or handle 22 is shown at 23, being preferably attached to the arm 19 by means of a barrel 24 engaged with a slightly raised pintle portion 25 intermediate the ends of the arm 19. Socket member 23 may be of any suitable construction, preferably being formed or stamped in a single piece from sheet-metal, the barrel 24 being initially flat and thereafter curled about the pintle portion 25, especially at leaves 26. Said socket member 23 may be reinforced by struck-out diverging ribs 27, and above the latter have a socket 30 proper 28 to receive the staff 22, which is preferably further secured by a screw or other fastening 29 passed through an opening in socket 28.

In attaching the connection 17 to the mop head as suggested in Fig. 3, frame 18 is inserted 45 into the space 15 by first inserting the ring 18 at its junction with arm 19, through opening 16 of web 13. The socket member 23 and staff are thereupon manipulated by turning and lateral movement to dispose the ring 18 in contact 50 with the barrier or stitching at 14. It will be realized that the web 13 at either side of the opening 16 may be slightly raised to facilitate the entry and threading of the ring 18 into the space 15. However, when the ring is within the 55 space, the mop head or the socket and frame

may be freely rotated relatively to each other, so that there will be no undue strain at any time of one on the other. This end is facilitated by having the opening 16 at the inner portion suitably enlarged to enable free rotation of the socket and by having the web 13 overlapped slightly inwardly of the stitching or barrier 14 as shown at 30.

Various changes may be resorted to within the spirit and scope of the invention.

What is claimed is:

A mop head having superposed webs, stitching securing said webs together and forming an annular barrier for coaction with a reinforcing frame having a periphery in the form of an interrupted circle and carrying handle-mounting means, the uppermost web having an opening therethrough within the confines of said barrier, said opening extending generally radially and being wider at the center of the uppermost web than adjacent the barrier, the uppermost web at the outer extremity of the opening and adjacent the barrier having portions overlapped for an appreciable distance radially of the uppermost web, said radial opening and overlapped portions 25 of the uppermost web being adapted to enable

application and removal of said frame by relative rotation of the frame and mop head and to enable turning of the frame within the mop head when in use without inadvertent separation of frame and mop head.
